The ornamental design for an RV or Marine toilet bowl discharge opening plug as shown and described.

DESCRIPTION

FIG. 1 is a top perspective view of the RV or Marine toilet bowl discharge opening plug according to the present invention;

FIG. 2 is a bottom perspective view of the RV or Marine toilet bowl discharge opening plug of FIG. 1;

FIG. 3 is a front view of the RV or Marine toilet bowl discharge opening plug of FIG. 1, the back view being the same;

FIG. 4 is a right side view of the RV or Marine toilet bowl discharge opening plug of FIG. 1, the left side view being the same;

FIG. 5 is a top view of the RV or Marine toilet bowl discharge opening plug of FIG. 1; and

FIG. 6 is a bottom view of the RV or Marine toilet bowl discharge opening plug of FIG. 1.

Portions or features of the RV or Marine toilet bowl discharge opening plug shown in broken lines in the drawings form no part of the claimed design. The use of stippling is intended to represent that the design is partially constructed of foam or a like absorbent material and does not form a surface feature of the design.
